UNITED STATES PATENT OFFICE

THOMAS PERRY TOWNES, OF LANDER, WYOMING, ASSIGNOR OF ONE-HALF TO MABEL FLESCHÉ, OF BASIN, WYOMING

CONVERTIBLE TABLE

Application filed October 8, 1930. Serial No. 487,349.

This invention relates to an improved convertible table which is expressly designed for use in hospitals, sanitariums and analogous places of confinement for the sick and invalid, and it has more particularly reference to a miniature convertible table such as may be conveniently supported directly on the bed in a position straddling the user.

The inventive conception comprehends a structure which is thoroughly practical and believed to be an unequal achievement in the prior art in that it is of unusual diversified construction and nature permitting it to fulfill the many requirements and needs of one confined to the bed.

Otherwise construed, the feature of versatility serves to provide a foldable knock-down portable table which may be conveniently used for eating, dressing, reading and the like.

Briefly stated, the structure embraces a table including a top provided with foldable legs, and an adjustable rack which is usable in one instance as a tray for eating, and in another instance for holding a book for expeditious and comfortable reading, and in the third instance as a writing desk and also as a mirror-equipped dressing table.

In the drawings:

Figure 1 is an end elevational view showing the device as it appears when set up to provide a dressing table.

Figure 2 is an end view showing the structure arranged to provide an eating tray.

Figure 3 is a front elevational view of the structure seen in Figure 1 disclosing the dressing mirror.

Figure 4 is a view showing the rack inverted and swung down on the table top to provide a writing desk.

Figure 5 shows the device adjusted to provide a book or paper rack to facilitate reading.

Figure 6 is an end view of the structure represented in Figure 4 with the legs and structure completely folded for convenient storage.

Figure 7 is a view like Figure 5 showing the rack swung outwardly beyond the table top so as to permit it to be rested on the chest of the user for more convenient reading.

Figure 8 is a front view of the structure seen in Figure 4 with the legs swung up to folded position.

In the drawings, the table is generally designated by the numeral 9. It comprises a suitable board top 10 having a vertical riser 11 on the rear longitudinal edge thereof. This riser constitutes a stop element as will be observed later. The legs are indicated by the numerals 12 and these are hingedly attached to the bottom of the table top as indicated at 13.

They can be swung down to table-supporting position as shown in Figures 3 and 4 for example, at which time they are maintained in this position through the medium of foldable stays 14. On the underside of the table are longitudinal stringers 15 forming guides and supporting means for article containing drawers 16. The drawers are arranged to slide out from the opposite ends of the table and designed to contain various useful articles.

The adjustable supports or rack is generally denoted by the numeral 17. This may be of diversified form but is preferably of the construction represented in the drawings. It comprises a board 18 of shape similar to the table top and slightly smaller than the table top. There are end flanges 19 and 20 and a front edge ledge forming strip 21. This forms a sort of tray or rack. This entire device 17 is attached to the ends of the table top through the medium of adjusting and connecting devices 22.

Each device comprises companion links 23 and 24 pivoted as at 25 and 26 to the complementary part. The links are joined together through the medium of a connecting bolt provided with an adjusting thumb nut 27. The device 17 is adjustable as a unit with the device 22 and is also adjustable individually with respect to said device 22. In other words, the device 17 is bodily swingable on the pivot 25 so as to permit it to be swung through an arc, allowing it to be inverted from the position shown in Figures 5 and 7 for example to the inverted tray-forming position shown in Figure 2. The flexibility of the connective devices 22 permits this.

In this connection, I invite attention to Figure 3, wherein it will be observed that the numeral 28 designates a mirror which may be built in or attached to the board 18 on the side opposite to the tray-forming side.

Referring first to Figure 1, it will be observed that the device is here set up to provide a dressing table. In accomplishing this result, the device 17 is disposed in a substantially vertical position or at right angles to the table top 10. The marginal flanges or inboards 19 and 20 at this time straddle or telescopically receive the stop strip 11. This exposes the mirror 28 toward the user. The complete device is set on the bedclothing directly in the bed and the legs are permitted to straddle the user in an obvious manner while the user is either in a sitting posture or in a reclined position.

The links of the retaining devices 22 take the approximate positions shown in Figure 1, at which time the thumb nuts 27 are securely tightened. By manipulating the devices 22 properly and swinging the device 17 bodily on its pivot it can be swung directly down on the table top 10 to assume a position as shown in Figure 2 at which time it provides a convenient eating tray.

The device 17 can be completely inverted to take the position shown in Figure 4 to provide a writing desk, at which time it defines a compartment between itself and the table top, said compartment being open at the front to accommodate stationary and writing articles. Most small articles however can be conveniently maintained in the sliding drawers which are movable to extending position beyond the opposite ends of the main table.

An additional adjustment of the device 17 permits it to be arranged either as shown in Figure 5 or Figure 7 for a convenient rack for holding newspapers, books, and the like to facilitate reading. The structure can be collapsed as shown in Figures 6 and 8 to facilitate storage, at which time the legs are folded against the bottom of the table and the device 17 folded down on the table top.

The links of the device 22 can take a position at this time to serve as retainers to prevent the drawers 16 from sliding out as shown in Figure 6. The gist of the idea is found in a structure comprising a miniature support, preferably in the nature of a small table having foldable legs and appropriate props or stays for holding the legs in adjusted position, wherein said table is fashioned as a support for a bodily adjustable device of a diversified nature having the multiple function of a tray, a mirror support, rack, writing desk, etc.

It is thought that persons skilled in the art to which the invention relates will be able to obtain a clear understanding of the invention after considering the description in connection with the drawings. Therefore, a more

lengthy description is regarded as unnecessary.

Minor changes in shape, size, and rearrangement of details coming within the field of invention claimed may be resorted to in actual practice if desired.

I claim:

A device of the class described comprising a table including a top, a pair of links, one at each of the two opposed sides of the table top, means for pivoting each link to the central part of said top, a link pivotally connected at one end to the free end of each of the other links, such pivoting means comprising a bolt and a nut, a tray, said tray including a bottom part and oppositely arranged extending flanges having its bottom part pivotally connected at its sides to the second set of links, a projection at the rear of the table for fitting between parts of the flanges when the tray is swung to vertical position at the rear of the table.

In testimony whereof I affix my signature.

THOMAS P. TOWNES.
